(57) **CLAIM**

The ornamental design for a fabric luggage handle assembly, as shown and described.

DESCRIPTION

FIG. 1 is a front perspective view showing the fabric luggage handle assembly embodying my new design.

FIG. 2 is a top view of the fabric luggage handle assembly shown in FIG. 1.

FIG. 3 is a front view thereof.

FIG. 4 is a rear view thereof.

FIG. 5 is a right side view thereof.

FIG. 6 is a left side view thereof.

FIG. 7 is a front perspective view showing the second embodiment of fabric luggage handle assembly embodying my new design.

FIG. 8 is a top view of the fabric luggage handle assembly shown in FIG. 7.

FIG. 9 is a front view thereof.

FIG. 10 is a rear view thereof; and,

FIG. 11 is a left side view thereof.

The unshown portions of the fabric luggage handle assembly do not form any part of the claimed design.
